ATTORNEYS.

UNITED STATES PATENT OFFICE.

EDNA HESTER BADGLEY, OF SPRINGFIELD, MISSOURI.

DESIGN FOR A TOY WAGON.

55,839.

Specification for Design.

Patented July 20, 1920.

Application filed April 2, 1920. Serial No. 370,890. Term of patent 7 years.

To all whom it may concern:

Be it known that I, EDNA HESTER BADGLEY, a citizen of the United States, residing at Springfield, in the county of Greene and State of Missouri, have invented a new, original, and ornamental Design for Toy Wagons, of which the following is a specification, reference being had to the accompanying drawing, forming part thereof.

The figure is a perspective view of a toy wagon showing my new design.

I claim:

The ornamental design for a toy wagon, as shown.

EDNA HESTER BADGLEY.
